UNITED STATES PATENT OFFICE.

SIMON SNYDER, OF MUNCY, PENNSYLVANIA, ASSIGNOR TO SPROUT, WALDRON AND COMPANY, OF MUNCY, PENNSYLVANIA, A CORPORATION OF PENNSYLVANIA.

APPARATUS FOR MIXING MOLASSES WITH STOCK FEED.

Application filed April 18, 1928. Serial No. 270,983.

This invention relates to apparatus for mixing dry granular materials or stock feed and molasses, and more particularly to a molasses feeder for vertical stock-feed mixing machine; the vertical mixer being adapted to be used for mixing different kinds of grain or granular materials used for feeding animals and having associated therewith means for feeding molasses to be mixed with 10 the food materials in the mixing chamber.

Mixing machines have been heretofore provided with means for mixing molasses with stock feed, and one object of my invention is to provide an apparatus of the character referred to with improved means for feeding molasses for admixture with grain or 15 granular materials conducted into the mixing chamber of a suitable mixing device, preferably of the vertical mixer type, in such manner as to avoid the formation of lumps 20 as in feed and molasses mixing machines as heretofore constructed, and to adapt the mixing device to be used independently of the means employed for feeding molasses to be 25 commingled with the food-stuff in the mixing chamber.

Much trouble and inconvenience has been experienced in cleaning out the mixing chamber and mixing devices in what are 30 known in the art as vertical mixers as heretofore ordinarily constructed, on account of the necessarily restricted space allowed to afford access to the interior of the chamber and the mixing device employed therein. 35 and another object of my invention is to avoid the trouble and inconvenience incident to cleaning such mixers, by providing a mixing chamber having a removable panel to afford access to its interior and to the mixing device therein for the purpose of cleaning 40 the same.

Other objects are to provide a simple and efficient molasses feeding device that will distribute the molasses upon the grain or granular materials within the mixing chamber in 45 small quantities at different points and to increase the efficiency of such machines and at the same time insure a more perfect mixture of the molasses with other ingredients.

The invention will first be hereinafter more particularly described, with reference to the accompanying drawings, which are to be taken as a part of this specification, and then pointed out in the claims at the end of 50 the description.

In said drawings, Fig. 1 is a side elevation of a mixing apparatus or machine which I preferably use in connection with a molasses feeding device embodying my invention;

Fig. 2 is a vertical sectional elevation of 60 a so-called vertical mixer having my improved molasses feeder attached thereto;

Fig. 3 is a detail sectional view on the line 3-3 of Fig. 1;

Fig. 4 is a top or plan view on a slightly 65 enlarged scale, partly in section, of the mixing chamber; the main driving shaft and gearing mounted thereon being removed;

Fig. 5 is a detail vertical sectional view, on a slightly enlarged scale, showing my improved molasses feeder fixed on the shaft 70 of the vertical mixer;

Fig. 6 is a plan view of the mixing chamber showing a modification of the molasses feeder, some parts being indicated in dotted 75 lines;

Fig. 7 is a detail vertical sectional view of the modified form of feeder shown in Fig. 6; and

Fig. 8 is a vertical sectional view on an 80 enlarged scale; the section being taken on a line extending longitudinally through the oblong panel and across the horizontal plates used for securing the upper and lower ends of the panel to the casing.

Referring to said drawings, in which the same reference letters are used to denote corresponding parts in different views, the letter A denotes a mixing chamber, which is preferably of cylindrical form, and which is 85 provided at its upper and lower ends with suitable bearings in which is journaled the shaft of a vertical mixing device or spiral conveyor B, said shaft having on its upper end a gear wheel C which meshes with a pinion d on a driving shaft D, on which is secured a gear wheel or pulley E to adapt the shaft to be driven by belt and pulley connection with a suitable motor. The mixing chamber and mixing device therein are 90 preferably of the construction shown in Patent No. 1,496,807, dated June 10, 1924, illustrating what is known in the art as a vertical mixer; the lower end-portion of the casing being of frusto-conical form and provided 95 with a suitable discharge opening or openings controlled by a slide valve or valves such as desired for discharging the contents of the mixing chamber into a spout or receptacle for receiving the same, and inasmuch as the ver- 100 105 110

tical mixer proper forms no part of my present invention, which is designed to be used in connection with mixing devices of any suitable construction, further description of 5 the vertical mixer appears to be unnecessary.

In using machines for mixing molasses with stock-feed it is frequently necessary to clean the interior wall of the mixing chamber and the mixing device or devices therein, 10 and to afford access to such chamber it has been the common practice to provide an opening or openings in the top thereof through which access is afforded to the interior of the chamber for the purpose of cleaning the 15 same, but this has been found to be inconvenient and troublesome at times, because of the limited space allowed by such openings for a person of small size to enter the chamber, and to obviate this trouble and inconvenience I provide the mixing chamber with 20 a removable panel constructed as follows.

As shown, a portion of one side of the casing A is cut away to provide an oblong opening, preferably of rectangular form, in which 25 is fitted and removably secured an oblong panel or closure plate G, which may be of concavo-convex form in cross-section to conform to the shape of the casing, and has its edges arranged in alignment with the adjacent edges of the casing around said cut-away 30 portion, so as to prevent the formation of any projection on the interior of the casing upon which the materials therein may collect and interfere with the mixing operation. On opposite sides of the opening are secured vertical metal strips or plates H of angular form or provided with apertured flanges to receive 35 fastening bolts or rivets for securing said plates to the casing along the margins of said opening, and similar horizontal plates or strips H¹ are secured to the casing in the same manner, one at the lower end of the opening and another at the upper end thereof; the edges of said cut-away portion of the 40 casing on opposite sides of the opening and at the upper end thereof being arranged to slightly overlap the angular plates secured thereto, while the angular plate at the lower end of the opening slightly overlaps the adjacent edge of the casing to which it is secured. Vertical and horizontal angular plates I and I¹, which are the counterparts 45 of the plates H and H¹, are secured along the edges or marginal portions of the panel G, so that the plates I slightly overlap the vertical edges of the panel, while the lower end of the panel overlaps the lower horizontal plate I¹, and the horizontal plate at the upper end of the panel slightly overlaps said upper 50 end; the two vertical plates at each side of the opening and the two horizontal plates at the upper and lower ends of the opening being secured together by fastening bolts inserted through the outwardly projecting 55 apertured flanges, thus firmly securing the

panel to the casing; the overlapping portions of the angular plates and the removable panel serving to effectually seal the joint between the panel and the casing proper, while the lowermost horizontal plate provides a 70 support for and an interlocking connection with the lower end of the panel, the upper end of which is adapted to be slightly raised so as to disengage the interlocking connection at its lower end so that the panel may be removed when the aforesaid fastening bolts are removed.

By the described construction the panel G is secured in place so as in effect to form an integral part of the mixing chamber or casing and provide a smooth interior surface that will not obstruct the downward passage of the material along the interior wall of the casing or cause the material to collect on said interior wall and consequently interfere with 80 the effectual mixing of the materials and the molasses to be commingled therewith. For convenience in removing and replacing the panel, it may be provided with one or more handles g on the outer side thereof, as shown. 90

The top or cover K of the mixing chamber has formed thereon or secured thereto, on the underside thereof, a depending annular flange k into which protrudes the upper end portion of a molasses cup or container L, secured on the vertical shaft so as to revolve therewith. The bottom of said cup is formed or provided with a centrally disposed tubular hub-like portion l, through which the vertical shaft passes, and a set screw l¹ serves to secure the cup upon the shaft with provision for vertical adjustment. In the form shown the cup consists of annular inner and outer upright members l² and l³, which are preferably formed integrally with the imperforate bottom and are spaced apart so as to provide an annular trough or liquid container. To prevent any liquid in the cup from rising high enough to overflow the inner annular member, the latter extends up around the stuffing box M depending from the under side of the top of the mixing chamber in which the vertical shaft is journaled at the top of the chamber. The molasses cup or container L is in communication with a source of supply through a pipe N having its delivery end protruding through the upper end of the mixing chamber and an aperture in the depending flange k for discharging molasses directly into the annular space between the annular upright members of the container, to which is secured a discharge tube or nozzle O, or a plurality of nozzles having their inner ends screwed into interiorly threaded apertures in the outer 100 annular member of the cup or container, as shown; said pipe O having perforations therein on its underside through which the molasses may drip or be discharged into the materials within the mixing chamber in small 105 110 115 120 125 130

quantities at different points at different distances from the vertical shaft and the inner wall of the mixing chamber. As shown in Figs. 4 and 5, the molasses cup is provided with a single distributing tube or nozzle, but two or more tubes or nozzles may be provided, as desired, and to prevent the liquid from being thrown out against the interior wall of the casing or mixing chamber by centrifugal force as the container revolves the distributing tube may have its outer end closed, as shown in Fig. 5, or turned downwardly as hereinafter described.

In Figs. 6 and 7 of the drawings is shown a modification of the distributing means. In this instance the molasses cup L^1 is provided with a plurality of discharge tubes or nozzles P of different lengths having their free ends turned downwardly to prevent the liquid from being thrown against the interior wall of the casing by centrifugal force. The discharge tubes or nozzles P , as shown, increase in length around the container; a short nozzle P being provided at one side of the cup, and longer nozzles P^1 , P^2 and P^3 arranged at equi-distances apart around the container and increasing in length in the order mentioned.

As will be seen, an unobstructed annular space is provided around the spiral conveyor, which is adapted to produce an upwardly moving column of material surrounding the conveyor and overturn and throw the same off into said annular space at the upper end of the conveyor, from which point the mixture is caused to descend by gravity through said annular space until it reaches the lower end of the conveyor when the material will be again raised centrally of the descending current and so on, thus overturning, agitating and mixing the materials until a thorough mixture is effected, whereupon the contents of the chamber may be discharged through a valve controlled discharge opening at the foot of the vertical shaft.

In operation, the dry materials to be mixed are placed in or conducted into the mixing chamber and mixed in the usual way by imparting motion to the mixing device within said chamber, either with or without the addition of molasses as an ingredient of the mixture, and when the desired mixture is effected the contents of the mixing chamber may be emptied into a suitable receptacle or conducted into a discharge spout at the lower end of the mixing chamber; the materials being mixed in batches of greater or less quantity and discharged from time to time as desired. When molasses is to be mixed with the soft dry feeds or grain or granular material, a valve in the feed pipe N , which is connected with a source of supply, is opened, and molasses, preferably heated so as to adapt it to run freely and prevent cold molasses from adhering to the feed pipe and distributing

means within the mixing chamber, is conducted into the revolving molasses cup and distributed as the cup revolves within the mixing chamber; the molasses being caused to flow by gravity when the heating chamber is located above the mixing chamber, or a pump (not shown) may be employed, when the source of supply is located below the mixing chamber.

Having thus described my invention, what I claim as new and desire to secure by Letters Patent of the United States is:

1. In combination with the mixing chamber of an apparatus for mixing dry pulverulent materials, a device for distributively and uniformly discharging molasses in small quantities into the materials undergoing a mixing operation therein, said device comprising a cup-like receiver revolvably mounted and axially adjustable within said chamber and having radially extended discharge nozzles through which molasses supplied thereto will drain into the mixing materials only in fine streams or drops, together with means for supplying molasses to said cup-like receiver.

2. In combination with a stock-feed mixing apparatus embodying a mixing chamber, and a mixing device revolvably mounted on a driving shaft arranged within said chamber, a molasses feeding and distributing device comprising a cup-like receiver adjustably fixed on said shaft to rotate therewith and having a radially extended discharge nozzle through which molasses supplied thereto will drain into the mixing chamber in only a fine stream or drops, together with means for supplying molasses to said distributing device.

3. A stock-feed mixing machine comprising an elongated vertically disposed mixing chamber, a mixing device fixed on a shaft revolvably mounted in said chamber, a liquid feeding and distributing means adjustably secured on said shaft to revolve therewith and comprising a tubular reservoir having a downwardly discharging nozzle extending radially therefrom through which liquid will drain into the mixing chamber only in a fine stream or drops, means preventing liquid from over-flowing the reservoir and down said shaft, and means for supplying liquid to said reservoir.

4. In combination with a pulverulent material mixing machine embodying a mixing chamber having an agitating device arranged therein; liquid distributing means revolvably mounted in said chamber comprising a liquid reservoir having a plurality of radially disposed discharge nozzles leading therefrom through which liquid will discharge downwardly in fine streams or drops, the said nozzles being formed to counteract the centrifugal force imparted to liquid discharged therethrough during revolution of the reser-

voir so as to prevent the liquid being thrown against the walls of the chamber, and means for supplying liquid to said reservoir.

5. In combination with a stock-feed mixing machine embodying an oblong vertically disposed mixing chamber having a vertically disposed spiral conveyor and mixing device arranged therein; a molasses distributing device revolvably mounted above said conveyor within said chamber, said device comprising a cup-like member providing a liquid reservoir concentrically of the conveyor shaft and having radially extending nozzles of different lengths leading therefrom to discharge the liquid downwardly in fine streams or drops into the mixing chamber, and means for supplying molasses to said cup-like member.

6. A liquid feeding attachment for stock-feed mixers, including agitators on rotatably driven shafts, comprising a base member having a hub-like portion with a central opening therethrough adapted to slidably fit on the mixer shaft and spaced annular wall members extending from said base member and therewith forming a liquid chamber concentrically of said shaft, together with a plurality of discharge tubes leading radially from said chamber and through which liquid supplied to the latter will distributively discharge into the mixer in fine streams or drops as the chamber is revolved with said shaft, and means for supplying the liquid to said chamber.

7. A liquid feeding attachment for stock-feed mixers including agitators on rotatably driven shafts, comprising a base member having a hub-like portion with a central opening therethrough adapted to slidably fit on the mixed shaft, spaced annular wall members extending from said base member and therewith forming a liquid chamber concentrically of said shaft, and a plurality of discharge tubes leading radially from said chamber through said liquid in the latter will dis-

charge into the mixer only in fine streams or drops, said tubes having their free ends turned downwardly to prevent throwing of the liquid against the walls of the mixer and being of lengths successively increasing around the liquid chamber.

8. A stock-feed mixing machine according to claim 3, wherein the elongate vertically disposed mixing chamber is provided with a removable panel having its inner surface conforming to and flush with the inner surface of the chamber, said panel being constructed with its lower end adapted to interlocking engagement with a fixture on the outer wall of said chamber and with its upper end releasably secured to said outer wall so that the panel may be raised and removed to afford access to the interior of said chamber.

9. A stock-feed mixing machine having an elongated vertically disposed mixing chamber provided with a removable panel closely fitting an oblong opening in one side of the chamber with its inner surface conforming to and flush with the inner surface of said chamber, said panel having secured thereto along its edges metal plates having outwardly projecting apertured flanges opposing flanges of similar plates secured on the outer side of the chamber, and fastening bolts inserted through the apertured flanges of the opposed sets of plates for detachably securing them together, thus adapting the panel to be removed to afford access to the interior of said chamber; the panel being supported at its lower end on one of said angular plates by an interlocking connection therewith and having its upper end slightly separated from and slidably connected with the adjacent edge of the casing so as to adapt the panel to be raised sufficiently to disengage the interlocking connection at its lower end and permit the panel to be removed.

In testimony whereof I affix my signature.
SIMON SNYDER.
